UNITED STATES PATENT OFFICE.

LEWIS S. CHAPMAN, OF SCHENECTADY, NEW YORK, ASSIGNOR TO GENERAL ELECTRIC COMPANY, A CORPORATION OF NEW YORK.

STARTING-RHEOSTAT.

No. 843,735.

Specification of Letters Patent.

Patented Feb. 12, 1907.

Application filed June 9, 1906. Serial No. 321,002.

To all whom it may concern:

Be it known that I, LEWIS S. CHAPMAN, a citizen of the United States, residing at Schenectady, county of Schenectady, State of New York, have invented certain new and useful Improvements in Starting-Rheostats, of which the following is a specification.

This invention relates to devices for controlling electric-motor circuits, and has for its object the provision of a device of this character which will protect the motor against accidents due to careless handling and other causes in a reliable, safe, and efficient manner.

15 My invention relates more specifically to protective devices for electric-motor circuits.

In the use of motor-starting devices having either an underload or overload release-magnet in connection with a reversing-switch it often times happens that the reversal is made quickly and that the motor, acting as a generator, will retain the controlling-arm in running position for a short time. During this interval if the switch is thrown 25 over to the reverse position the motor may be destroyed by a dangerous rush of current, due to the fact that there is no protective resistance in series. This might also happen with a non-reversing switch which is opened 30 and closed quickly.

It is the object of my invention, therefore, to provide a device which will positively prevent the occurrence of such an accident. In carrying out my invention, therefore, I 35 provide, in connection with the reversing-switch on a motor-starting panel, means whereby when the reversing-switch is open the retaining-magnet of the starter is short-circuited, making the return of the arm to off position absolutely certain. When the 40 switch is then thrown over to the reverse position, the short circuit of the magnet is again opened, thereby energizing the retaining-magnet.

45 In the accompanying drawings, in which I have shown one embodiment of my invention, Figure 1 is a plan view of a starting-panel embodying my improvements. Fig. 2 is a detail of the reversing-switch, and Fig. 3 is a diagram of the circuit connections.

50 Referring to the drawings, 10 is a slate or soapstone base of a starting-panel provided with a starting-rheostat, a reversing-switch,

and a line-switch. The starting-switch simply comprises a series of contacts 11, forming 55 terminals for starting resistance 12, a starting-arm 13, pivoted at 14 for engagement with the contacts 11, and a no-voltage magnet 15 for retaining the arm in running position. The line-switch 16 is of the usual knife-type, being preferably a double-pole knife-switch, while the reversing-switch may be of any desired type, but is also preferably a double-pole knife-switch pivoted at 17 and 18, so as to provide a double throw for reversing the current. In Fig. 2 I have shown a detail of this switch, which is designed to short-circuit the retaining-magnet 15 when it is open. The switch-blades are pivoted so as to engage clips 19 and 20 on one side of 70 the pivot and clips 21 and 22 on the opposite side thereof.

For the purpose of closing a short circuit through the retaining-magnet I provide a plunger 23 directly under the cross-bar 24 of 75 the switch and arranged to slide back and forth through the switch-base 10. A spring contact-strip 25 is secured under the pivotal point of the switch by means of bolts 26 and normally closes a metallic contact with the 80 conductors 27 and 28 through the contacts 29 and 30, respectively. When, however, the switch is closed, the circuit between the contactor 27 and spring-contact 25 is opened on the side corresponding to the position of 85 the switch, this being accomplished by the cross-bar 24 forcing the spring-contact 25 away from the contact 29 through the agency of the plunger 23. When the plunger is closed by the opening of the switch, the 90 spring-contact 25 forces the plunger up and makes contact at 29. A similar operation takes place on the opposite side, so as to open and close the circuit between the spring-contact 25 and the conductor 28 at contact 30. 95

The arrangement of circuits with the reversing-switch in the position shown and the controlling-arm 13 moved to starting position is as follows: Current passes from the positive main at 31 through the line-switch to 100 clip 19, thence through the reversing-switch to center contact 17, thence through wire 32, armature 33, wire 34, controlling-arm 13, starting resistance 12, wire 35, contact 18, contact 20, wire 36, wire 37, through the line-switch, and back to line at 38. The field 105

2
is connected across the line from 40 and 41. The starting-arm being moved to running position will be retained in this position by the magnet 15, which is connected across the line from 40 through wire 42, resistance 43 to 41 through wires 36 and 37. If now it is desired to reverse the motor, the armature of the motor continuing to run for a time will energize the magnet 15, and thus retain the 5 arm 13 in short-circuited position. With my arrangement, however, when the switch is open the magnet 15 is short-circuited through conductor 27, strip 25, and conductor 28, thus deenergizing the magnet. When 10 the switch is thrown over to the opposite position, this circuit is again opened, thereby reenergizing the magnet.

It will thus be seen that I have provided a 15 simple and convenient arrangement for preventing the destruction of a motor by the careless use of a reversing-switch.

It should be understood, of course, that 20 the device is capable of use in other connections than that shown and that many modifications of the particular device which I have 25 shown for purposes of illustration will suggest themselves to those skilled in the art without departing from the spirit of my invention as set forth in the annexed claims.

30 What I claim as new, and desire to secure by Letters Patent of the United States, is—

1. The combination with a starting-rheostat having a no-voltage magnet, of a reversing-switch, and means controlled thereby for 35 deenergizing the said magnet.

2. The combination with a starting-rheostat having a no-voltage magnet, of a switch in the motor-circuit, and means controlled by the opening of said switch for short-circuiting the said magnet.

3. The combination with a starting-rheostat having a no-voltage magnet, of a reversing-switch, and means controlled by the open-

ing of said switch for short-circuiting the said magnet.

4. The combination with a starting-rheostat having a no-voltage magnet connected across the line, of a reversing-switch in the motor-circuit, and means controlled by the actuation of said switch for deenergizing the 50 said magnet.

5. The combination with a starting-rheostat having a no-voltage magnet connected across the line, of a reversing-switch in the motor-circuit, and means for short-circuiting 55 the said magnet on the opening of said switch.

6. The combination with an electric motor, of a switch in the motor-circuit biased to open position, an electroresponsive device for maintaining said switch in the closed position, a reversing-switch, and means for deenergizing the said electroresponsive device on the actuation of said reversing-switch.

7. The combination with an electric motor, of a switch in the motor-circuit biased to 60 open position, an electromagnetic device responsive to no voltage connected across the line and arranged to maintain said switch in the closed position, a reversing-switch, and means for deenergizing the electromagnetic 70 device by the actuation of the said switch.

8. The combination with an electric motor, of a switch in the motor-circuit biased to open position, an electromagnetic device responsive to no voltage connected across the 75 line and arranged to maintain said switch in the closed position, a reversing-switch, and means for short-circuiting said electromagnetic device by the opening of said reversing-switch.

In witness whereof I have hereunto set my hand this 8th day of June, 1906.

LEWIS S. CHAPMAN.
